DRILLING DEVICE

Joseph Maximus Pestarini, Staten Island, N. Y.

Application October 6, 1949, Serial No. 119,974

10 Claims. (Cl. 255—3)

1

This invention relates to drilling machines. More particularly the invention concerns drilling devices used in mining, construction and related operations.

An object of this invention is to provide improved means for increasing the operative efficiency of a drilling device by imparting to the drill bit simultaneous rotating and percussing action. The percussing action is obtained, by repeated impacts on the drill bit.

Another object of the invention is to provide in combination with a drilling device, improved motor means, for operating the device, said means being adapted to stall without injury to the motor or its associated circuits, and further adapted to develop, while stalled, a relatively high torque; said motor means being adapted, further, to maintain a safe maximum speed.

A further object of this invention is to provide in combination with a drilling device an electric motor, supplied with a current, the intensity of which is kept below a predetermined limit irrespective of the rotational speed of the drill bit and electromagnetic means for percussing the drill bit while it rotates, said electromagnetic means being adapted to be supplied with a pulsating current.

The accompanying figure illustrates, schematically, an arrangement embodying the invention.

In the figure, 1 indicates the drilling device comprising a bit 2, a driving motor 3 for rotating the bit and transmitting its torque to said bit by means of a slideable mechanical coupling 4, mounted on the armature shaft thereof, which allows reciprocatory movement of the bit as it rotates. An electromagnet including winding 5, adapted to be energized intermittently and a movable armature 8 provides reciprocatory, percussive movement of the bit. Said movable armature 8 is adapted to engage a shoulder 32 on a rear portion of the tool bit 2, each time the electromagnet is energized, thus imparting a percussive action to the bit through repeated impacts.

The driving rotating motor 3 is shown as a motor metadyne provided with an armature having four brushes per cycle, a, b, c, d, stator windings 6, 7 and controlling rheostats 21, 22.

The current is supplied to the motor 3 by a generator metadyne 9 shown in the figure as comprising an armature provided with four brushes per cycle. Two primary brushes a', c', are short circuited and two secondary brushes b', d', are connected to the primary brushes a, c, of the motor metadyne 3. The metadyne 9 is also pro-

2

vided with a stator winding 14 and a control rheostat 26 for controlling the output current that the generator 9 supplies through its secondary brushes b', d'.

5 In the loop comprising the generator metadyne 9 and the motor metadyne 3, two other energy consumers 23, 24, such as motors or the like, may be inserted and supplied with energy by the metadyne 9 for operation independently of the motor metadyne 3.

The metadynes mentioned herein are rotating electric machines comprising an armature with a commutator and more than two brushes per cycle. The metadynes have been described in 15 many United States patents, see for instance, Patents Nos. 2,055,240; 1,987,417; 2,038,380; 2,049,389; 2,079,465. A more complete description is given in Revue Generale de l'Electricite, on March 8 and 15, August 16 and 23, November 22 20 and 29 and December 6, 1930, Paris.

A motor metadyne of the type referred to hereinabove is more fully described in the United States patent application, Serial No. 707,698, filed November 4, 1946. A generator metadyne of the 25 type referred to hereinabove is more fully described in the British Patent No. 420,167.

Another generator metadyne 10 is shown supplying energy to the winding 5 of the electromagnet and is indicated as comprising two short circuited primary brushes a'', c'', and two secondary output brushes b'', d'', per cycle. A stator winding 15 traversed by the output current, creates a flux opposing the armature flux created by said output current. Another stator winding 16 controls, by its ampere turns, the output current.

The generator metadynes 9 and 10 are indicated as mounted on a common shaft which is driven by a prime mover not shown. On the 40 same shaft is mounted a small auxiliary dynamo 11 shunt excited through its field winding 17 and supplying direct current to an auxiliary circuit having conductors 30 and 31.

A consumer 25, such as a motor or the like, 45 may be inserted in the loop supplied with energy by the generator metadyne 10 for operation independently of the operation of drill 1.

The generator 9 creates a practically constant current, the intensity of which is controlled by the ampere turns of the stator winding 14 which is energized by the constant voltage circuit through conductors 30, 31. The rheostat 26 controls the current traversing winding 14.

The generator 10 is adapted to create impulses 50 of current at a low frequency. Said impulses are

controlled by a pulsating current traversing the stator winding 16. Such pulsating current is obtained by opening and closing a circuit carrying a relatively small current, by means of a rotating interruptor 13. The device 13 is provided with a metallic contact member 33 fixed on a rotating cylinder of insulated material upon which bear two brushes 21. The cylinder of the interruptor 13 is rotated by means of a small dynamo 12 shunt excited through its field winding 18 and connected to the conductors 30, 31.

The frequency of the pulsating current created by the generator 10 is determined by the speed of rotation of the interruptor 13 which speed is controlled by a rheostat 20 inserted in the field winding circuit of the dynamo 12. The intensity of the same pulsating current is regulated by the rheostat 19 inserted in the circuit of the winding 16.

For each pulsation of the current traversing the winding 5 of the electromagnet, the armature 8 is operated. The shoulder 32 on the bit is subjected to an impact while said bit is also rotated through coupling 4.

It is important to note that the losses due to the frequent interruption of the current occur only in the small current carrying circuit of the stator winding 16 and are zero in the circuit comprising the armature of the generator metadyne 10 and the winding 5 of the electromagnet.

The constant current supplied by the generator 9 to the motor 3, traverses the armature of said motor and the stator winding 7, creating thus a starting torque of a predetermined value. The value of said torque may be regulated by the rheostat 21 connected in parallel with the winding 7. The winding 6 traversed by the secondary current supplied by the secondary brushes, b, d, of the motor metadyne 3, creates a flux in the opposite direction and larger than the flux created by the secondary current of the motor metadyne traversing its armature. The range of motor speed is determined by means of rheostat 22. Therefore, with increasing speed, the torque diminishes and at a predetermined speed the torque becomes zero. With a substantially constant current input, the motor metadyne 3 may be operated in a range of speeds between zero and maximum and may be stalled without damage and on the other hand cannot exceed a predetermined speed although it is supplied with constant current.

An arrangement of devices and circuits has thus been described, which is adapted to accomplish the various objects of this invention in a highly efficient manner under circumstances of practical use.

It is understood that while the arrangement of parts described herein, is adapted to provide combined rotary and percussive or impact action for the drill bit, the operating devices including the metadynes and electromagnet may be operated to provide rotary or impact action for the drill bit, independently of each other.

It is also understood that tools other than drill bits, which require combined rotary and impact action in use, may be operated by the combination of devices as described above.

As various possible embodiments might be made of the above invention, and as various changes might be made in the embodiment above set forth, it is to be understood that all matter herein set forth or shown in the accompanying drawing, is to be interpreted as illustrative and not in a limiting sense.

I claim:

1. A drilling device comprising a drill bit, means for rotating said bit including an electric motor, means for simultaneously percussing said tool including an electromagnet, coupling means between said rotating means and said bit permitting axial movement of said bit while said bit is rotating, dynamo electric means for supplying substantially constant electric current to said electric motor at all speeds of said motor and means for supplying a pulsating current to said electromagnet.
2. A drilling device comprising a drill bit, means for rotating said bit including an electric motor of the metadyne type, means for simultaneously percussing said tool including an electromagnet, means for supplying said motor metadyne with direct current comprising a metadyne generator, means for supplying said electromagnet with a pulsating current, said last mentioned means including a second metadyne generator, said second metadyne generator being provided with a controlling stator winding traversed by a pulsating current and means for modifying the frequency of said last mentioned pulsating current.
3. A drilling device comprising a drill bit, means for rotating said bit including a motor metadyne, said motor metadyne being provided with an armature, a pair of primary brushes and a pair of secondary brushes per cycle and with a plurality of stator windings, means for simultaneously percussing said bit including an electromagnet, means for supplying the primary brushes of said motor metadyne with a substantially constant current, means for supplying said electromagnet with a pulsating current of a predetermined frequency, one of said stator windings having its magnetic axis substantially coincident with the axis of the flux created by the current traversing the armature through its secondary brushes, being traversed by said constant current, another of said stator windings, being traversed by said last mentioned armature current and creating a flux opposing and greater than the last mentioned armature flux and means for controlling the ampere turns created in the first mentioned stator winding.
4. A drilling device comprising a drill bit, means for rotating said bit including electric motor, means for simultaneously percussing said bit including an electromagnet, means for supplying said electromagnet with a pulsating current, said last mentioned means comprising a generator metadyne provided with a controlling stator winding, a circuit including said winding, means for periodically interrupting the current in said circuit, and means for varying the rate of interruption of the current in said circuit.
5. A drilling device comprising a drill bit, means for rotating said bit including an electric motor, means for simultaneously percussing said bit including an electromagnet, means for supplying said electromagnet with a pulsating current, said last mentioned means comprising a generator metadyne provided with an armature, output brushes and a plurality of stator windings, one of said stator windings controlling the output current, being traversed by a pulsating current of a predetermined frequency and another of said stator windings being connected in series with the output brushes of said generator metadyne and creating a flux opposing the armature flux due to the current traversing the armature through said output brushes.
6. A drilling device comprising a drill bit,

means for rotating said bit comprising a motor metadyne, said motor metadyne including an armature, a pair of primary brushes and a pair of secondary brushes per cycle, and a plurality of stator windings, means for supplying the primary brushes of said motor metadyne with a substantially constant current, one of said stator windings having its magnetic axis substantially coincident with the axis of the flux created by the current traversing the armature through the secondary brushes being traversed by said constant current, another of said stator windings being traversed by said last mentioned armature current and creating a flux opposing and greater than the last mentioned armature flux, and means for controlling the ampere turns created in the first mentioned stator winding.

7. A drilling device comprising a drill bit, means for imparting a percussive and reciprocatory action to said drill bit comprising an electromagnet, means for supplying a pulsating current to said magnet comprising a generator metadyne, said metadyne including a stator winding for controlling the output current thereof, means for supplying said stator winding with a pulsating current and means for modifying the frequency of said last mentioned pulsating current.

8. A drilling device comprising a drill bit, means for rotating said bit including an electric motor, said motor including a field winding creating ampere turns decreasing with an increase in the speed thereof, means for percussing said bit including an electromagnet, means for supplying said motor with a substantially constant current at speeds ranging from zero to maximum, means for supplying said electromagnet with a pulsating current of predetermined frequency.

9. In combination, a tool and means for imparting combined rotary and impacting movement to said tool comprising electromagnetic means, rotary electrical means for supplying current to said electromagnetic means, said rotary electrical means comprising a control winding, a source of direct current, interruptor means in circuit with said source of current and said con-

trol winding for pulsating the current traversing said control winding whereby to affect the output current of said rotary electrical means supplied to said electromagnetic means and to provide impulse operation thereof, electric motor means, means for coupling said motor to said tool, rotary electrical means for supplying said motor with current, said last mentioned rotary electrical means including a control winding in circuit with said source of current for controlling the current output of said last mentioned rotary electrical means.

10. Means for rotating a tool comprising in combination, means for supplying substantially constant current, a motor adapted to be operatively connected to said tool, said motor comprising an armature including a pair of primary brushes and a pair of secondary brushes displaced therefrom, a stator winding in circuit with said secondary brushes, a second stator winding in circuit with said current supply means and said primary brushes, said motor being adapted to operate under stalling conditions without injury thereto.
